ANTIFOULING OF FIREARMS

Charles Hardy, Pelham Manor, N. Y., assignor to
 Hardy Metallurgical Company, New York,
 N. Y., a corporation of Delaware

No Drawing. Application January 9, 1941,
 Serial No. 373,809

5 Claims. (Cl. 52—5)

This invention is concerned with anti-fouling agents for use in firearms and contemplates the use of certain metallic hydrides to reduce fouling of gun barrels by explosion products. More specifically, my invention contemplates the inclusion in a propellant explosive charge of a metallic hydride that decomposes at temperatures attained in the explosion.

In accordance with my invention, an appropriate metallic hydride, preferably in finely-divided form and in relatively small proportion as compared to the explosive charge, is disposed in sufficiently intimate relationship to a propellant charge of explosive, preferably nitro-explosive, that the heat of the explosion decomposes the hydride with release of the metal and of hydrogen. These products of the hydride operate to reduce the fouling that otherwise would occur in the barrel of the firearm in which the charge is exploded. Thus, my invention contemplates in the explosion of an explosive (particularly a nitro-explosive) in a firearm, the improvement which comprises reducing fouling of the firearm by the products of explosion by decomposing a metallic hydride in the zone of explosion during the occurrence thereof.

A number of metallic hydrides, including those of sodium, potassium, boron, antimony and calcium, are suitable for use in the practice of my invention. These hydrides are reasonably stable at atmospheric temperatures and pressures but decompose at temperatures within the range attained when a confined explosive charge is ignited. Thus, calcium hydride, which is a presently preferred example of a material appropriate for use in accordance with my invention, decomposes into calcium and hydrogen at a temperature of about 770° C., which is substantially below the temperature of 2000° C. that may be attained in a chamber in which a nitro-explosive, for example, nitrocellulose, is exploded. The other hydrides mentioned decompose at even lower temperatures but are, in general, less stable than calcium hydride.

The metallic hydride may be incorporated directly into the explosive charge, or it may be separated therefrom by a capsule wall, a wad, or other barrier which keeps the hydride and the explosive from coming in contact with each other prior to explosion. The imposition of the barrier is a desirable precaution in cases where the explosive employed may react with the particular hydride at relatively low temperatures or pressures. In other cases, as when calcium hydride is employed as an anti-fouling agent for

nitrocellulose or the like, the hydride may be mixed intimately with the powder charge.

Generally speaking, the proportion of hydride to employ will be small, of the order of a few grams per pound of explosive.

The hydrogen released through decomposition of metallic hydrides under the conditions prevailing during the explosion is especially active, probably because it is in "nascent" or atomic state. This hydrogen, as well as the metal derived through decomposition of the hydride, may react with gaseous or solid products of the explosion to reduce corrosion of the gun barrel, or to reduce fouling thereof by solid products. In any event, the inclusion of a small proportion of calcium hydride or other suitable hydride in an explosive charge is recommended for its beneficial effect upon the active life of the gun barrel through reducing corrosion or erosion, or the amount of solids that remain deposited in the barrel.

Calcium hydride, which I prefer to employ, especially with nitro-explosives such as nitrocellulose, is a brittle bluish substance that may be reduced to granular form by ordinary mild crushing. It may be formed in various ways, for example, by passing hydrogen gas in contact with metallic calcium at a temperature of about 375° C.

It is desirable to include a small proportion of the metallic hydride in each explosive charge. Thus, when the charges are disposed in cartridges, each cartridge should contain a small proportion of the hydride together with the explosive. Thus, the hydride may be placed at the rear of the cartridge adjacent the primer and separated from the main explosive charge by a fragile wad which disintegrates or decomposes when the explosion occurs and permits contact between the decomposition products of the hydride and those of the explosive. When the explosive charge is contained in powder bags or the like, a capsule containing the hydride may be loaded in the gun breech along with the bagged charge.

The use of decomposable metallic hydrides, and particularly calcium hydride, as anti-fouling agents, is especially useful in conjunction with nitro-explosives, particularly nitrocellulose.

I claim:

1. A propellant explosive charge containing a metallic hydride that decomposes at the temperature of explosion.
2. A propellant explosive charge containing a relatively small proportion of a metallic hydride

that decomposes at the temperature of explosion.

3. A propellant nitro-explosive charge containing a relatively small proportion of a metallic hydride that decomposes at the temperature of explosion.

4. A propellant nitro-explosive charge containing a small proportion of calcium hydride.

5. A propellant explosive charge having incor-

porated therein a relatively small proportion of a metallic hydride that decomposes at the temperature of explosion, the hydride being separated from the balance of the charge by a barrier which permits contact of the products of explosion and of the hydride when explosion occurs.

CHARLES HARDY.
